UNITED STATES PATENT OFFICE.

GEORGE N. SIMPSON, OF CHICAGO, ILLINOIS.

HOPPER AND CAR.

Application filed March 11, 1925. Serial No. 14,708.

To all whom it may concern:

Be it known that I, GEORGE N. SIMPSON, a citizen of the United States, residing at Chicago, in the county of Cook and State of

5 Illinois, have invented a new and useful Improvement in Hoppers and Cars, of which the following is a specification.

This invention relates to improvements in hoppers and cars, and more especially to a 10 hopper adapted to receive material and load the same into a car. The apparatus as here shown may be used, for example, in mining material by what may be termed the continuous loading process. By this process, 15 I mean, the continuous discharge of material into a hopper by means of a loading machine or otherwise, and the intermittent removal of material from said hopper by a car. Such a process, for example, may be 20 used by placing a loading machine at the face of the material which has been shot, and permitting the same to discharge a continuous stream of material into a hopper close by. The loading machine and hopper being at the face of the material within a room are ordinarily not readily accessible by the ordinary mine cars, and therefore, 25 a shuttle car is used to transport material from the hopper to the stub entry or room entry where the shuttle car is unloaded, and its contents discharged into the regular mine cars operating in the cross entry. In order to illustrate my invention, 30 therefore, I have here shown such a hopper and shuttle car. It is obvious, however, that the apparatus here shown is adapted for other uses than the one referred to.

In that form of device embodying the features of my invention shown in the accompanying drawings, Figure 1 is a view in side elevation of my improved hopper and car, Fig. 2 is a similar view in top plan, Fig. 3 is a longitudinal section of the same showing the car almost entirely under the hopper, Fig. 4 is a view similar to Fig. 3 showing the car at the end of its travel under the hopper, Fig. 5 is a similar view showing the car just as it is leaving the hopper, and Fig. 6 is a transverse vertical sectional view.

As shown in the drawings, 10 indicates the discharge end of a loading machine adapted to supply a continuous stream of material to the hopper. Material may be supplied to the hopper in this manner or in any other manner. Loading machines thus

designed to pick up shot material from the face and discharge it in a stream, are old in the art and form no part of the present invention.

11 indicates, in general, the hopper which is substantially rectangular in shape made out of sheet metal or other suitable material and is here shown as having its sides made rigid and strengthened by means of the angle members 12 fastened thereto. The hopper 11 is supported in any suitable manner, as, for example, by means of the adjustable legs 13. Vertically movable pins 14 are provided, the same being adapted to be thrusted upwardly into the roof of the room in order to assist in holding the hopper firmly in position.

15, 15 indicates the rails upon which the shuttle car 16 is adapted to operate. The body of the hopper is supported a sufficient distance above the rails 15 and the legs 13 give a sufficient spread so that the shuttle car 16 is adapted to move on the rails 15 into a position under the hopper.

In the operation of the device, the shuttle car 16 moves to the left (as viewed in Fig. 1) to a position under the hopper, the end of its travel being indicated by the position occupied in Fig. 4. In leaving the hopper, the car moves in the opposite direction, that is, to the right (as viewed in Fig. 1). The end of the hopper at which the car enters and leaves, I refer to as the front thereof. The end of the car that enters the hopper first and leaves last, I have referred to as the front of the car. The bottom of the hopper 11 as divided into two transverse sections which are substantially equal in area, except that the back section is somewhat larger than the front section. The back of the hopper is closed by a slanting rigid end plates 17. The back bottom section I have indicated by 18 and the front bottom section by 19, both of which sections comprise longitudinally slidable plates supported at their edges on guides, the plate 18 resting on the guides 18^a and the plate 19 on the guides 19^a; said guides 18^a and 19^a comprising the horizontal flanges of a channel iron as shown. The plate 18, as shown, is adapted to slide under the plate 17, and likewise the plate 19 slides under the plate 18. When both of these plates are substantially entirely under the plate 17 as shown in Fig. 4, it will be seen that the bottom of the hopper has substantially all

of its area open. This is as wide as the bottom can be opened.

Means are provided whereby the movement of the shuttle car 16 to a position under 5 the hopper opens the bottom so that the hopper will discharge a load of material into the car. As the car moves from under the hopper, the bottom is automatically closed.

The plate 19 is provided on its under 10 side with three angle irons, namely, 20 at the front edge, 22 at the rear edge, and 21 substantially at the center. The plate 18 is provided with two angle irons on its under side, namely, 23 at the forward edge and 24 15 at the rear edge.

The shuttle car 16 is provided with a transversely arranged shaft 25 carried by the bearings 26. The ends of the shaft 25 are provided with short arms 27 carrying on 20 their ends anti-friction rollers 28 adapted to enter the guides 29 at the sides of the hopper. Between the bearings 26 the shaft 25 also carries two forwardly projecting short arms 30 having pivotally mounted on 25 their ends vertically movable latch bars 31 extending substantially to the upper edge of the front end of the car. It will be seen that rocking of the shaft 25 will move the latch bars 31 upwardly or downwardly. 30 Rocking of the shaft 25 will be caused by movement of the rollers 28 in the guides 29, said guides having depressions therein to cause said rocking as will be described more in detail hereinafter.

35 The latch bars 31 have virtually two operative positions, one when they are up so that their ends will engage the angle irons 20, 21 or 22, and one when they are down so that they will clear these angle irons. In 40 the further description, therefore, I will refer to these latch bars as being up or down. It will be noted that the bottom surfaces of the guides 29 have two levels, as shown in Fig. 4, the higher level being indicated by 29^a and the lower level by 29^b and 45 29^c.

The operation is as follows. As the car 50 approaches the hopper, the rollers 28 enter the front ends of the guides 29. The front part of the guide 29^b is low so that the latch bars 31 will be in their lower position. Suitable stops are provided to prevent the latch bars or rollers 28 from falling below their lower position. Consequently, the rollers 28 will enter the front ends of the 55 guides 29. Since the latch bars are in their lower position, the upper ends will clear the angle iron 20 thus causing no opening of the bottom of the hopper at the start. After the latch bars have cleared the angle iron 20, the rollers 28 will strike the inclines 29^d in the guides 29 thus lifting the rollers up to the higher level 29^a and consequently raising the latch bars 31. Upon further 60 movement of the car forward, the ends of 65

the latch bars will engage the angle iron 21 on the sliding plate 19. Further movement forward of the car will therefore slide this plate open until the angle iron 32 on the upper side at its rear edge engages the angle iron 24 on the plate 18. Thereupon both plates together will be moved to the left until the rollers 28 reach the declines 33 in the guides 29. The car is shown in this position in Fig. 3. At this point, the rollers 70 75 28 will be forced down by the slant 33 or drop down to the lower levels 29^c thus releasing the latch bars 31 from the angle iron 21 and allowing both the plates 18 and 19 to remain stationary until such latch bars 80 85 31 are again raised by the higher level of the guides so that they will engage the angle iron 22 at the rear edge of the plate 19. Thereupon, further movement of the car to its final position as shown in Fig. 4 will 90 95 serve to move both plates 18 and 19 further to the left, giving the hopper its widest opening.

As the car leaves the hopper, the operation is as follows. The plates 18 and 19 at 95 first remain stationary until the latch bars 31 engage the strip 21. The plate 19 is then moved to the right until it is released by the rollers dropping down to the low portion 29^c of the guides 29. The latch bars then are moved up again so that upon further movement of the car to the right they will 100 engage the strip 20 thus pulling the plate 19 further to the right until the angle iron 32 105 engages the angle iron 23. Further movement of the car to the right will then pull both plates to their closed position as shown in Fig. 5 and finally, as the car leaves the hopper, the rollers 28 will descend the decline 29^d so that the latch bars 31 will be 110 disengaged from the strip 20 permitting the car to leave the hopper.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to 115 claim all novelty inherent in my invention as broadly as possible in view of the prior art.

I will now describe more in detail some of the features of the invention. It is to be noted that as the car enters the hopper the sliding plate 19 is first moved. This causes material in the front end of the hopper to discharge into the front portion of the car. That is, all the material lying on the plate 19 falls into the front portion of the car. After the angle iron 32 engages the angle iron 24 on the plate 18 both plates will slide together until the car reaches the position shown in Fig. 3. Obviously during this movement of the 120 125 130 135

plates 19 and 18 together, some of the material on top of the plate 18 will also fall into the forward portion of the car. It is to be noted, however, that when the car reaches the position shown in Fig. 3, the latch bars will drop so that both plates 18 and 19 remain stationary until the latch bars again engage the angle iron 22. During this further movement of the car with both plates 19 and 18 stationary, the rear portion of the car will advance nearer to the right hand or discharge edges of the plates 18 and 19 so that further movement of the car into the hopper after the latch bars 31 have engaged the angle iron 22 will cause discharge of material from the top of the plate 18 into the rear portion of the car. In other words, stated generally, the apparatus is so designed that upon movement 20 of the car into the hopper the front portion of the car will first be filled and then the rear portion. Because of this construction, the car will be fully loaded, and the load will be evenly distributed in the car. Moreover, the hopper will be practically entirely emptied. For example, if the hopper contains only enough material for one carload, and such material is spread substantially uniformly over the bottom of the 30 hopper; all of such material will be emptied from the hopper into the car to give the latter a full load. For example, assuming that there is only one carload of material in the hopper, evenly distributed over the bottom sections 18 and 19, the operation will be somewhat as follows. The car upon entering will first go partway under the sliding section 19 before the bottom is opened at all. The section 19 will then slide to discharge material into the front portion of the car, the same substantially filling the front portion of the car and flowing under the section 19. Both sections will then move together to discharge more material into the car until the car reaches the position shown in Fig. 3. From this point, both sections will remain stationary, while the car moves forward until the latch bars 31 engage the angle iron 22. This will bring the rear portion of the car up to the discharge edges of the plates 18 and 19 so that further movement of the car into the hopper will cause the remaining material on the plate 18 to fall into the back portion of the car, thus 50 completely and evenly filling the car and entirely emptying the hopper.

It is to be noted also that the apparatus is so arranged that as the car begins to move under the hopper, it will not commence to open the bottom until it has moved a short distance thereunder. That is, there will be no opening of the bottom until the latch bars 31 engage the angle iron 21. The front end of the car will therefore be partly under the plate 19 before the discharge

of material into the front portion of the car commences. This overlapping of the extreme front end of the car by the plate 19 provides room for the material to flow thereunder, thus causing a much more even and better filling of the car, smoother and better operation of the parts, and less danger of any spillage.

What I claim as new, and desire to secure by Letters Patent, is:

1. A hopper adapted to receive a continuous supply of material; a car adapted to receive a load of material from the hopper; means for supporting the hopper a sufficient distance above the floor to permit the car to go under the same; a sliding bottom section at its forward end of said hopper; a part on said section at its forward edge; another part on said section substantially back of the forward edge; a movable part on the car; means whereby said movable part on the car will move to a position so that it will pass the part on the front edge of the movable section as the car goes under the hopper and engage the part back of the forward edge as the car moves further under the hopper whereby said sliding section is opened by such further movement of the car under the hopper; means whereby, upon movement of said car from a position under the hopper, said movable part will move to a position so that it will engage the part on the front edge of the movable section and close the same; and means whereby said movable part on the car will move to a position so that it will be disengaged from the part on the front edge of the movable section as the car leaves the hopper.

2. A hopper adapted to receive a continuous supply of material; a car adapted to receive a load of material from the hopper; means for supporting the hopper a sufficient distance above the floor to permit the car to go under the same; a movable bottom section at the front end of the hopper; a part on said bottom section near the front edge thereof; another part on said movable section back of the front edge; a movable part on the front end of the car; a guide on the hopper having different levels; a shoe on the car adapted to enter said guide as the car goes under the hopper; a connection between said shoe and the movable part on the car whereby said movable part is raised when the shoe is in the higher level of the guide and lowered when said shoe is in the lower level of the guide; the levels of said guide being so arranged that as the car enters the hopper, the movable part on the front part of the car will be lowered to pass the part on the forward edge of the movable bottom section and raised to engage the part on the bottom section back of the forward edge to open said section, and upon the car leaving the hopper the movable part thereon will be

moved so that it will clear the part on the front edge of the movable bottom section.

3. A hopper adapted to receive a continuous supply of material; a car adapted to receive a load of material from the hopper; means for supporting the hopper a sufficient distance above the floor to permit the car to go under the same; a longitudinally slid-
5 able bottom section in the hopper at the front end thereof; means whereby movement of the car to a position under the hopper will first permit said bottom section to remain stationary, then move the same with the car, then permit the same to remain
10 stationary, and then move the same with the car until said car reaches its final position under the hopper; and means whereby said car, upon moving away from its final position under the hopper, will close said
15 bottom section.

4. A hopper adapted to receive a continuous supply of material; a car adapted to receive a load of material from the hopper; means for supporting the hopper a sufficient dis-
20 tance above the floor to permit the car to go under the same; a longitudinally slid-
25 able bottom section in the hopper at the front end thereof; means whereby movement of the car to a position under the hopper will first permit said bottom section to remain stationary, then move the same with the car, then permit the same to remain stationary, and then move the same with the car until
30 said car reaches its final position under the hopper; and means whereby movement of said car away from its final position under said hopper will first permit said bottom section to remain stationary, then move said bottom section toward closed position,
35 then permit said section to remain stationary, and then move said bottom section to fully closed position.

5. A hopper adapted to receive a continuous supply of material; a car adapted to receive a load of material from the hopper, and adapted to move to and from a position under said hopper; means for supporting the hopper a sufficient distance above the floor to permit the car to go under the same; a longitudinally slid-
45 able bottom section at the front end of said hopper; a second slid-
50 able bottom section back of said first named section; a part on the forward bottom section; a part on the car adapted to engage said part on the forward bottom section after the car has moved partway under the hopper, whereby further movement of the car will carry said front section with said car; means whereby movement of the forward bottom section to open position will slide the back bottom section also to open position; and means whereby movement of said car from a position under said hopper will close both said bottom sections.

6. A hopper adapted to receive a continuous supply of material; a car adapted to receive a load of material from the hopper, and adapted to move to and from a position under said hopper; means for supporting the hopper a sufficient distance above the floor to permit the car to go under the same; a longitudinally slid-
60 able bottom section

section at the front end of said hopper; a second slid-
65 able bottom section back of said first named section; means whereby movement of the car to a position under the hopper at first permits both said slid-
70 able sections to remain stationary, then moves the first mentioned section toward open position, then moves both sections to open position; and means whereby movement of said car from a position under said hopper will close both said slid-
75 able bottom sections.

7. A hopper adapted to receive a continuous supply of material; a car adapted to receive a load of material from the hopper, and adapted to move to and from a position under said hopper; means for supporting the hopper a sufficient distance above the floor to permit the car to go under the same; a longitudinally slid-
80 able bottom section at the front end of said hopper; a second slid-
85 able bottom section back of said first named section; means whereby movement of the car to a position under the hopper at first permits both said slid-
90 able sections to remain stationary, then moves the first mentioned section toward open position, then moves both sections toward open position, then permits both sections to remain stationary, and then moves both sections to fully open position; and means whereby movement of said car from a position under said hopper first permits both
95 said slid-
100 able sections to remain stationary, then moves the forward section toward closed position, and then moves both sections to fully closed position.

8. A hopper adapted to receive a continuous supply of material; a car adapted to receive a load of material from the hopper, and adapted to move to and from a position under said hopper; means for supporting the hopper a sufficient distance above the floor to permit the car to go under the same; a longitudinally slid-
105 able bottom section at the front end of said hopper; a second slid-
110 able bottom section back of said first named section; a part on the forward bottom section; a part on the car adapted to engage said part on the forward bottom section after the car has moved partway under the hopper, whereby further movement of the car will carry said front section with said car; means whereby movement of the forward bottom section to open position will slide the back bottom section also to open position; and means whereby movement of said car from a position under said hopper will close both said bottom sections.

9. A hopper adapted to receive a continuous supply of material; a car adapted to receive a load of material from the hopper, and adapted to move to and from a position under said hopper; means for supporting the hopper a sufficient distance above the floor to permit the car to go under the same;

- 5 a longitudinally slidable bottom section at the front end of said hopper; a second slid-
able bottom section back of said first named section; a part on the forward bottom sec-
tion; a part on the car adapted to engage
5 said part on the forward bottom section
after the car has moved partway under the
hopper, whereby further movement of the
car will carry said front section with said
10 car; means whereby movement of the for-
ward bottom section to open position will
slide the back bottom section also to open
position; and means whereby movement of
said car from a position under said hopper
15 will close both said bottom sections; said
opening and closing means comprising a
movable latch on the car adapted to engage
parts on the front section and operated by
a shoe in a guide on the hopper.
- 20 10. A hopper adapted to receive a con-
tinuous supply of material; a car adapted
to receive a load of material from the hop-
per; means for supporting the hopper a suf-
ficient distance above the floor to permit
25 the car to go under the same; and means op-
erated by movement of the car to a position
under the hopper for discharging material
from one section of the hopper into one por-
tion of the car and from another section of
30 the hopper into another portion of the car.
11. A hopper adapted to receive a con-
tinuous supply of material; a car adapted
to receive a load of material from the hop-
per; means for supporting the hopper a suf-
ficient distance above the floor to permit
35 the car to go under the same; and means op-
erated by movement of the car to a position
under the hopper for discharging material
from the front section of the hopper
40 into the front portion of the car and from
the back section of the hopper into the back
portion of the car.
12. A hopper adapted to receive a con-
- tinuous supply of material; a car adapted
45 to receive a load of material from the hop-
per; means for supporting the hopper a suf-
ficient distance above the floor to permit
the car to go under the same; a slidable bot-
tom section at the front end of the hopper;
50 a second slidable bottom section back of said
first named section; and means whereby
movement of the car to a position under said
hopper at first opens said front bottom sec-
tion and then permits the same to remain
55 stationary and then opens the back section.
13. A hopper adapted to receive a con-
tinuous supply of material; a car adapted
to receive a load of material from the hop-
per; means for supporting the hopper a suf-
ficient distance above the floor to permit the
60 car to go under the same; a slidable bottom
section at the front end of the hopper; a
second slidable bottom section back of said
first named section; and means whereby
movement of the car to a position under
65 said hopper at first opens the front section,
then opens both sections simultaneously,
then permits both sections to remain sta-
tionary and then opens both sections sim-
70 ultaneously.
14. A hopper adapted to receive a con-
tinuous supply of material; a car adapted
to receive a load of material from the hop-
per; means for supporting the hopper a suf-
ficient distance above the floor to permit
75 the car to go under the same; a slidable bot-
tom section at the front end of the hopper;
a second slidable bottom section back of said
first named section; and means whereby
movement of the car to a position under
80 said hopper at first opens the front section,
and then opens both sections simulta-
neously.

Witness my hand and seal this 28 day of
February, A. D. 1925.

GEORGE N. SIMPSON. [L. s.]
